ATTACHING MEANS FOR WALL FIXTURES
AND THE LIKE

Louis Sharpe, Chicago, Ill., assignor to Franklin
Brass Mfg. Company, Chicago, Ill., a copart-
nership consisting of Louis Sharpe and Harry
S. Shapiro

Application November 25, 1935, Serial No. 51,425

2 Claims. (Cl. 248—200)

This invention relates to certain novel im-
provements in attaching means for wall fixtures
and the like, and has for its principal object the
provision of an improved construction of this
5 character which will be highly efficient in use
and economical in manufacture.

Among the several objects of this invention is
to provide a fixture in which the means of at-
tachment between a wall and the fixture is con-
10 cealed from view.

A still further object of this invention is the
provision of a fixture having means for concealing
the attaching means between the fixture and
the wall, and which concealing means is of a sim-
15 ple structure easily and readily capable of being
applied in its respective position with respect to
the fixture.

Other objects will appear hereinafter.

The invention consists in the novel combina-
20 tion and arrangement of parts to be hereinafter
described and claimed.

The invention will be best understood by ref-
erence to the accompanying drawing showing the
preferred form of construction, and in which:

25 Fig. 1 is a perspective view of the fixture em-
bodying the invention;

Fig. 2 is a sectional detail view of the same
taken substantially on line 2—2 of Fig. 1;

30 Fig. 3 is a perspective view of a wall plate em-
bodied in the invention; and

Fig. 4 is a fragmentary perspective view of the
attaching arm embodied in the invention.

Heretofore in the art of attaching fixtures, such
as bathroom fixtures or the like, to a wall or other
35 stationary object, it was the practice and custom
of providing in the wall plate of the fixture per-
forations, and then projecting through these per-
forations the attaching screws or bolts. After
40 the fixture was properly attached to the wall or
other stationary object, the heads of these at-
taching screws or bolts were visible and often-
times disrupted the symmetric design of the fix-
ture.

The present invention as heretofore stated is
45 concerned with a fixture in which the attaching
means for effectuating attachment between the
fixture and the wall is concealed from view.

In accomplishing these and other obvious ob-
jects of the invention, the fixture illustrated in
50 the drawing comprises a supporting arm 10,
which in the present instance is designed to sup-
port a drinking glass or the like. This arm 10
may be in the form of a hook for the purpose of
supporting a towel or other bathroom or kitchen
55 linen, or it may be in any form or design capable

of supporting articles of various description, such
as are suspended in the kitchen or bathroom of a
home.

I, therefore, do not wish to be limited and do
not predicate my invention upon the particular
5 design, shape or formation of the arm 10.

This arm 10 preferably is provided with a neck
portion 11, to the rear of which is an upstanding
lug 12 intended and designed to be flatly dis-
posed against the wall 13 or other stationary ob-
ject. 10 Between the neck 11 and the lug 12 there
is provided a recess 14, and communicating with
this recess 14 is a perforation 15 formed in the
neck 11.

The lug 12 is provided with perforations 16,
and projected through these perforations are the
attaching elements 17 which at the present time
are in the form of flat-headed screws; the de-
sign and shape of these attaching elements may
vary according to the requirement. 20

The wall plate is indicated at 18, and this wall
plate 18 may be of any approved design or style,
having formed in the back portion thereof a re-
cess 19 communicating with a notch 20 terminat-
ing in a transversely extending groove 21 at 25
the bottom portion of the plate. Formed in the
wall 22 of the plate 18 is a tapped opening 23
adapted to receive a connecting screw 24, as
shown in Fig. 2.

The recess 19 of the plate 18 is adapted to re-
ceive the upstanding lug 12 when the shank portion
25 of the neck 11 is received in the trans-
versely extending groove 21 with the adjacent
portion of the upstanding lug confined in the
notch 20, thereby permitting the plate 18 to be 35
flatly disposed against the wall 13 in position
to conceal the upstanding lug 12 and its attach-
ing elements 16.

The plate 18 and fixture arm 10 may be plated
or otherwise decorated to increase the aesthetic
40 appeal to the eye of the observer.

The fixture when completed presents an un-
broken design, and this in one instance is the
result of the plate 19 concealing the means of
attaching the fixture to the wall. 45

The transversely extending groove 21 serves
to properly locate the plate 18 with respect to
the neck 11, so that the plate 18 will be properly
centered with respect to the fixture arm 11. It
also provides the means of receiving the shank 50
25 whereby connection is effectuated between the
plate 19 and the fixture arm 10.

While I have illustrated and described the
preferred form of construction for carrying my
invention into effect, this is capable of variation 55

and modification without departing from the spirit of the invention. I, therefore, do not wish to be limited to the precise details of construction set forth, but desire to avail myself of such 5 variations and modifications as come within the scope of the appended claims.

Having thus described my invention, what I claim as new and desire to protect by Letters Patent is:

- 10 1. A fixture comprising a wall plate having a recess formed therein and a notch communicating with the recess, a member adapted to support an article and including a shank portion providing a reduced portion engageable in the 15 notch of said plate for locating the plate with reference to said member and having a lug adapted to bear against and be attached to a wall,

means providing attachment between the wall and the lug, said lug being confined in the recess and concealed by the plate, and means providing connection between the wall plate and the reduced portion of the shank.

2. In a fixture a wall plate having a recess formed therein and a notch communicating with the recess, a member adapted to support an article and including a shank, a portion of which is adapted to be confined in the notch for locating the wall plate with respect to the said member, said shank providing an attaching lug for attaching the said member to a wall, and means for attaching said lug to said wall, said lug being confined in the recess and concealed by the plate. 15

LOUIS SHARPE.
